MILK BOTTLE HOLDER

Peter Heinz, Brooklyn, N. Y.

Application April 23, 1937, Serial No. 138,580

7 Claims. (Cl. 232—42)

This invention relates to milk bottle holders and in particular to devices of this type in which the milk after delivery is prevented from being stolen.

5 A particular object of the invention is to provide, in a door or wall facing the exterior of a building, a tray or the like which is arranged to receive the delivered bottles of milk, and which may be subsequently moved to a position inside 10 the building by novel mounting means used in connection with such tray or shelf upon which the milk bottles are deposited.

A still further object of the invention is to provide in a wall or door, a swinging panel door 15 which has hinged thereto a foldable tray which when the device is not in use, can be maintained in position out of the way and which, when positioned for use permits the milkman to set bottles on the tray without using his hands to manipulate any of the parts of the device.

Still further objects of the invention reside in the novel features of the device which permit its being opened for use, and held in opened or bottle receiving position against accidental closure and 25 further permits the weight of the bottles to position the tray member so that the door carrying said tray may be swung closed by the foot to position the bottles inside the main door or wall to prevent theft.

30 In devices of this kind in which the milkman has to manipulate parts to lock bottles in place, it has been found that the milkman will neglect to place the bottles where they belong in the device or will not bother to manipulate parts because the delivery entails the carrying of a rack 35 of milk bottles in one hand and several bottles in the other hand and when the milkman has to drop his rack or put down bottles at each stop, he loses time in delivery and it is therefore a feature of my invention to provide a device in which the milkman places the bottles with one hand and leaves the device to operate automatically to swing the bottles inside the door or wall of the dwelling where it cannot be stolen.

45 Changes and variations may be made in the construction shown and described without departing from the principles of the invention or sacrificing its chief advantages; hence such invention is not to be confined to the precise structure shown in the drawing, in which:

Figure 1 is a view of the inside of a door of a dwelling in which, for convenience of illustration, my improved bottle holder is incorporated.

50 Figure 2 is an enlarged section taken on the line 2—2 of Figure 1.

Figure 3 is a fragmentary view in end elevation of a panel door on which a bottle tray or plate is hingedly mounted, the tray being shown in two positions and also illustrating how the bottle can be used to force the tray to horizontal position, 5

Figure 4 is a fragmentary view in perspective showing the mounting of the tray or bottle plate on the panel door,

Figure 5 is an enlarged fragmentary view of the edge of the tray door and tray showing the relation of the tray in two positions to a detent member, and

Figure 6 is a fragmentary plan view of the tray as illustrated in Figure 5 and the detent member.

Referring to the drawing in detail, 10 indicates 15 a door of usual type providing access to a dwelling and made with lower panels 11, in an opening 12, of one of which is provided a small door 13, hereinafter referred to as the tray or plate door, and which is hinged as at 14 to the panel 20 adjacent said opening. The closed and open positions of door 13 is indicated in outline and full line respectively in Figure 2. While the device is disclosed in connection with a door, it can be mounted in any exterior dwelling wall. 25

One edge of the plate door is provided with a latch 15 and a stop strip 16, while the hinges 14 are provided with coil springs 17 which tend to swing the door closed and will close the door when the tray 19 is in horizontal position. The tray, 30 plate or flap 19 is hinged as at 18 to the tray door 13. The tray is preferably made of metal and is semi-circular in shape. It is provided with an edge flange 20 to prevent the one or more bottles which can be placed on the tray from sliding off 35 when the tray door closes after the bottles have been placed on said tray, the bottles being indicated by the numeral 21A. The flange 20 is tapered or decreased in height at its ends as at 21 to permit the plate 19 or tray to flip up to the 40 position shown in Figure 3 when no bottle is on the tray, the taper limiting the upward swing of the tray under influence of springs by contact with one side of the door 13. The plate is yieldably retained in raised or closed position by the 45 springs 22 which are mounted on the hinges 18.

When the device is not in use, it assumes the position shown in Figure 3, the tray or plate 19 being in its "up" position. When set for delivery of milk thereto, the latch 15 is operated to permit 50 door 13 to swing out through opening 12. The door is prevented from swinging back under the influence of springs 17 by a snap detent 23 mounted on the wall or panel 11 and with which the flange 20 contacts when the tray or plate 19 is in 55

- "up" position. When the tray is down or in horizontal bottle supporting position, the flange thereon clears the detent 23 and permits the door 13 to swing closed and be latched closed by latch 15. 5 The detent 23 has an inner bevel 24, which permits passage of the plate 19 when the door swings outwardly, the plate or tray camming the detent out of the way.

In operation, for instance, at night the tray door 10 13 is unlatched and swung outwardly and is prevented from swinging back in by the detent 23. When the milkman pushes the tray down with the bottle as seen in Figure 3, said tray or plate 15 19 will be in horizontal position and will clear the detent 23 and the springs 17 on the door hinge will swing the door closed and latch it, with the result that the bottles will be inside the dwelling and the 20 operation being automatic also relieves the milkman of any necessity of using his hands to manipulate the parts of the device. The placing of the bottles on the tray permits the springs to close the door 13. It is evident that the door 13 can be made wider than shown to afford a partial covering for the opening 12 when the device is open or 25 in "set" position.

The hinge 18 may be provided with a lip 25 which will prevent the tray from dropping lower than a horizontal position. Also the latch 15 will prevent the door 13 from being opened from 30 the outside, and the strip 16 will provide a closing stop as well as weather sealing strip.

My invention is not to be restricted to the precise details of construction shown since various changes and modifications may be made therein 35 without departing from the scope of the invention or sacrificing its chief advantages.

What I claim is:

1. In a bottle holder, in combination, a door, a tray mounted on said door for supporting bottles, 40 hinges connecting the tray to the door whereby said tray can assume a horizontal bottle supporting position, the door being swingable outwardly to receive bottles, and means for preventing the door from closing when the tray is empty.
- 45 2. In a bottle holder, in combination, a door mounted for horizontal hinged movement to open and closed positions, a spring for urging the door closed, a bottle tray mounted on said door for vertical hinging movement from horizontal to raised position, a spring for yieldably holding the

tray in raised position, and a detent engageable by the tray when the latter is in raised position to prevent the door from closing.

3. In a bottle holder, in combination, a door mounted for horizontal hinging movement to open and closed positions, a spring for urging the door closed, a bottle tray mounted on said door for vertical hinging movement from horizontal to raised position, a detent engageable by the tray when the latter is in raised position to prevent the door from closing and means for limiting the upward swinging movement of the tray and holding an edge thereof away from the door whereby said tray can be engaged by a descending bottle and forced to horizontal position. 5

4. In a bottle holder as set forth in claim 3 wherein said tray is arranged to pass said detent when bottles are in the tray. 10

5. In a bottle holder, in combination, as set forth in claim 3 wherein the tray is provided with an upstanding flange. 20

6. In a bottle holder, in combination, a door mounted for horizontal swinging movement to open and closed positions, a spring for urging the door closed, a bottle tray mounted on said door for vertical swinging movement from horizontal to raised position, a detent engageable by the tray when the latter is in raised position to prevent the door from closing, means for limiting the upward swinging movement of the tray and holding an edge thereof away from the door whereby said tray can be engaged by a descending bottle and forced to horizontal position, and said tray being arranged to clear the detent when in horizontal position so that the door will automatically close 30 when bottles are placed in the tray. 35

7. In a bottle holder, in combination, a door mounted for horizontal hinging movement to open and closed positions, a spring for urging the door closed, a bottle tray mounted on said door for vertical hinging movement from horizontal to raised position, a spring for yieldably holding the tray in raised position, a detent engageable by the tray when the latter is in raised position to prevent the door from closing, and said tray being arranged to clear the detent when in horizontal position so that the door will automatically close 40 when bottles are placed in the tray. 45

PETER HEINZ.
